CHARLES GULDEN.

UNITED STATES PATENT OFFICE.

CHARLES GULDEN, OF NEW YORK, N. Y.

DESIGN FOR A BOTTLE.

SPECIFICATION forming part of Design No. 13,868, dated April 24, 1883.

Application filed December 5, 1882. Term of patent 7 years.

To all whom it may concern:

Be it known that I, CHARLES GULDEN, of New York, in the county and State of New York, have invented a new and original Design for a Bottle, of which the following is a specification.

The accompanying photograph represents a face view of a bottle containing my design.

This invention relates to a new ornamentation of a bottle.

The round body A of the bottle represents to the eye a series of upright ribs, *a*, which extend from the bottom upward and terminate at their upper ends near a small bead, which separates them from the plain neck of the bottle. On one side of the bottle is set, into the aforementioned corrugated portion, a star-like ornament, *b*, which is not corrugated.

I do not limit myself so far as the invention

of a corrugated bottle is concerned to its connection with the star-like ornament *b*, as said ornament is not seen on every side of the body, and also as it may be replaced by another ornament.

I claim—

1. The design for a bottle, having upright continuous ribs *a a* along the round body, said ribs being separated by a bead from the plain flaring neck of the bottle and extending from the bottom of the bottle to said bead, substantially as shown.

2. The design for a bottle, having corrugations *a* on its body and the star-like ornament *b*, substantially as shown.

CHARLES GULDEN.
